UNITED STATES PATENT OFFICE.

ROBERT S. GROGAN, OF CHICAGO, ILLINOIS, ASSIGNOR OF ONE-HALF TO CHICAGO GRANITINE MANUFACTURING COMPANY AND ONE-HALF TO CHARLES WESELY CO., BOTH OF CHICAGO, ILLINOIS, AND BOTH COMPANIES ORGANIZED UNDER THE LAWS OF ILLINOIS.

METALLIC RIM FOR MOLDED RECEPTACLES.

Application filed July 3, 1924. Serial No. 724,169.

To all whom it may concern:

Be it known that I, ROBERT S. GROGAN, a citizen of the United States of America, and a resident of Chicago, county of Cook, and State of Illinois, have invented a new and useful Improvement in Metallic Rims for Molded Receptacles, of which the following is a specification.

The main objects of this invention are to provide an improved form of metallic rim for molded receptacles, such as concrete laundry tubs, trays, sinks, and the like; to provide a rim of this kind having an improved construction and arrangement of telescoping parts to permit adjustment of the rim; and to provide an adjustable metallic rim which is simple in construction and adapted to be readily assembled.

An illustrative embodiment of this invention is shown in the accompanying drawings, wherein:

Figure 1 is a perspective view of a tub having one of the improved rims applied thereto.

Fig. 2 is an enlarged fragmentary plan of one corner of the rim.

Fig. 3 is a bottom view of the same.

Fig. 4 is a transverse section taken on the line 4—4 of Fig. 2, and showing also part of one wall of the tub.

Fig. 5 is an enlarged fragmentary perspective view of one corner of the tub, showing the rim applied thereto.

In the most common forms of adjustable rims for molded receptacles heretofore in use, each of the rim sections has been provided with interlocking portions, such as tongues and slots, formed adjacent the ends thereof and arranged so that the tongues of one side section were adapted for engagement with the slots of an adjacent side section. The formation of the interlocking portions directly on the side sections necessitated the cutting of these sections to the exact lengths required for each particular receptacle to which the rim was applied, and inasmuch as these receptacles varied in size, it was necessary for the receptacle manufacturer to carry a large stock of rim sections of various lengths. Moreover, such finished

smaller size without the necessity of altering the position of one of the interlocking portions of such sections.

In the specific construction herein shown, the present invention is applied to a rim wherein the main side sections are secured together by corner sections which telescopically engage the ends of the side sections. The corner sections are all substantially identical in construction and are adapted for use with all of the various sizes of rims. With this improved rim construction, the side sections may be rolled out or otherwise formed in long strips, which may then be cut to the desired lengths.

In the form shown in the drawings, the improved rim comprises side sections 1 and corner sections 2 telescopically arranged so as to initially permit a relative adjustment of the rim sections. As illustrated, the rim is applied to the upper edges of a concrete tub 3.

The sections 1 and 2 are preferably sheet metal stampings, which may be cut and formed in a single operation. Each of the side sections 1 comprises an upper face 4, which is substantially the same width as the walls of the tub, and a depending flange 5 forming an outer side face which lies flat against the walls of the tub. Extending inwardly from the faces 4 and 5, are flanges 6 and 7 respectively, which are embedded in the material of the receptacle walls, so as to anchor the rim sections to the receptacle.

The corner sections 2 include upper faces 8 and outer side faces 9, which embrace the corresponding faces 4 and 5 of the side sections, and inwardly extending flanges 10 and 11 which embrace the corresponding flanges 6 and 7 of the side sections and which are also anchored in the walls of the tub. The opposed ends of the faces 9 are recessed, as shown at 12, so as to eliminate any sharp edges at the corners of the tub and to present a finished appearance.

In molding the receptacle, the side sections 1 and corner sections 2 are assembled and placed at the bottom of the mold in an inverted position, so that the concrete which is poured into the mold will force the side sections downwardly into firm contact with

the corner sections. The inwardly extending flanges 6, 7, 10 and 11 become embedded in the concrete and anchor the rim to the tub. By this improved rim construction, 5 the telescoping sections are firmly secured together without the use of solder, rivets or other similar fastening means.

Although but one specific embodiment of 10 this invention has been herein shown and described, it will be understood that numerous details of the construction shown may be altered or omitted without departing from the spirit of this invention as defined by the following claim.

15 I claim:

The combination with a molded receptacle, of a polygonal rim comprising side sections, corner sections telescopically engaging the ends of said side sections and arranged to initially permit a relative adjustment of said side sections, and depending flanges extending along the edges of said sections and projecting inwardly so as to be anchored in the material of the receptacle, the flanges of said corner sections 20 embracing the flanges of said side sections.

Signed at Chicago this 30th day of June 1924.

ROBERT S. GROGAN.
